PRESSURE VESSEL AND SUPPORT

Patrick D. Hishon, William D. Carter, and Thomas N. Ravn, Berkeley, and Herbert L. Borchers, San Francisco, Calif., assignors to Shell Development Company, San Francisco, Calif., a corporation of Delaware

Application August 14, 1944, Serial No. 549,468

12 Claims. (Cl. 23—290)

The present invention relates to pressure vessels and more particularly to an improved autoclave and means for supporting the same.

In the various chemical and related industries, in research laboratories and the like, pressure vessels are often required in which the reactions and behavior of materials under advanced pressure and temperature conditions may be studied. Similar vessels are also required in many industries for the preparation of various materials on a commercial scale by blending, reacting, polymerizing or otherwise treating prescribed ingredients under conditions of pressure and temperature. In view of the extremely high working pressures often utilized in carrying out operations of these general types, the equipment employed, particularly the reaction vessel or autoclave, has conventionally been exceedingly cumbersome and heavy, necessitating several operators to charge or discharge the same and unduly long periods of time to seal the vessel after charging the same.

It is an object of the present invention to provide an improved autoclave assembly which is readily and easily charged and discharged. Another object is to provide an autoclave assembly in which the autoclave may be easily and readily tilted for cleaning or other operations. A further object is to provide an autoclave assembly embodying an improved autoclave closure wherein the closure securing elements are under compression load only. A still further object is to provide an autoclave assembly with improved drainage means for the autoclave vessel. Another object is to provide an autoclave assembly with readily demountable external heating means and independently mounted internal heating means. Still another object is to provide an autoclave with efficient externally driven agitating means, improved means for sealing the agitator shaft against the pressure within the system, improved means for lubricating the agitator shaft and means for preventing leakage of materials from within the autoclave around the agitator shaft.

Other objects, together with some of the advantages to be derived in utilizing the present invention, will become apparent in the following detailed description thereof, taken together with the accompanying drawings forming a part of the specification, and wherein:

Figure I is an elevation, partly in section, of an autoclave assembly according to the invention, with the autoclave in raised and sealed position;

Figure II is an elevation of the assembly shown

in Figure I with the autoclave in lowered and tilted position;

Figure III is a sectional elevation of the autoclave unit shown in Figures I and II at 8.

Referring particularly to Figures I and II, a base member 1 is provided with a column flange 32 supporting an upright tubular column member 2. Carriage member 3 is slidably mounted on column member 2 and is provided with guide collars 4 and 5 which slidably engage guide rod 6 which is also supported by column flange 32 and extends upwardly parallel to column member 2. Clamp ring 7 is rigidly mounted on column member 2 near the upper end thereof and limits the maximum upward travel of carriage member 3. The upper end of guide rod 6 is rigidly positioned and secured by clamp ring 7. Drive support 30 is rigidly mounted on the upper end of column member 2 and is provided on one side with motor mounting 34 which supports drive motor 27, which is of the variable speed type and controlled through control box 28 mounted thereon. Electric power is supplied to motor 27 through cable 29. On the opposite side of column member 2, drive support 30 supports bearing housing 22, agitator shaft housing 21 and retainer ring 18, agitator shaft 19 passing through these elements and terminating above bearing housing 22. An agitator 20 is mounted on the lower end of agitator shaft 19 and a pulley wheel 23 is mounted on the upper end thereof. A second pulley wheel 24 is mounted on the drive shaft of motor 27 and drives pulley wheel 23 and agitator shaft 19 through drive belt 25. Safety housing 26 encloses pulley wheels 23 and 24 and drive belt 25.

Support bracket 37 is rigidly mounted on carriage member 3 and supports autoclave unit 8 which is pivotally and offcenter mounted on support bracket 37 at 9.

Counterbalance weight 18 is supported within column member 2 by means of roller chain 11 which engages and passes over cog wheel 12 mounted at the upper end of column member 2. The opposite end of roller chain 11 is attached to autoclave unit 8 by means of bracket 14, the intermediate length of chain passing beneath a second cog wheel 10 which is mounted on the upper end of carriage member 3. Cog wheel 12 is driven by a conventional worm gear unit indicated generally at 35.

In Figure III, jacket flange 40 threadededly engages autoclave 38 at 41, a plurality of threaded bolts as at 40 passing through jacket flange 40 and engaging ring member 41 which is rigidly

mounted on the outer shell 42 of the heating jacket. Inner shell 43 of the heating jacket is spaced from outer shell 42 by means of a plurality of spacer screws 82 which pass through ring member 81 in threaded engagement therewith, through outer shell 42 and urge against inner shell 43. Flange 79, formed of thermally insulating material, is disposed between jacket flange 40 and ring member 81 and also serves as a spacer between jacket flange 40 and the heating jacket. Bracket 14 is rigidly attached to ring member 81 and outer shell 42 of the heating jacket. Inner shell 43 and outer shell 42 of the heating jacket are rigidly attached to sleeve element 83 at their lower ends and spaced from discharge outlet 50 of autoclave 33 by means of spacer washers as at 48 which are formed of thermally insulating material and are slideable upon discharge outlet 50. A plurality of heating elements, as at 47 are disposed within inner shell 43 of the heating jacket and are spaced from each other by means of annular insulators 44, 45 and 46, insulator 44 being supported by a shoulder provided in inner shell 43 and insulators 45 and 46 being supported by a plurality of hangers as 25 at 84 which are in turn supported by insulator 44. Electric power is supplied to heating elements as at 47 by means of electric cable 17 which passes through insulator 49 in the heating jacket. Electric cable 17 also leads to control box 15 mounted on carriage member 3 and is supplied current by cable 16 leading from a source of electric energy (Figure II).

The autoclave bottom closure and drain comprises a bushing 51 threadedly mounted in discharge outlet 50, nipple 85 being formed as a part of bushing 51 and extending upwardly in discharge outlet 50 as shown. Bushing 52 is threadedly mounted in the end of nipple 85 and supports a multi-disc edge type filter 54, grooved adjustment rod 53 passing through filter 54 and bushing 52 and terminating in nipple 86. Head 87 of rod 53 presses against the top of filter 54 and coil spring 88 contacting the bottom of bushing 52 and a nut 88 threaded on the bottom of rod 53 urges the rod downwardly. Thus, the compression forces exerted on the discs of the filter may be adjusted by adjustment of nut 88. The filter arrangement may be removed from the discharge outlet 50 as a unit by removal of bushing 51, since the other elements of the unit are all either directly or indirectly supported thereby.

The lower end of agitator shaft housing 21 is shaped to fit closely in a socket joint with an annular shoulder formed on the inside of autoclave 33 near the upper end thereof at 39, the shaft housing thus forming the primary closure for the autoclave. An annular corrugated gasket 37, preferably formed of soft steel or other deformable metal, is provided in an annular channel formed in the body of autoclave 33 and shaft housing 21, the gasket receiving channel being disposed immediately above the joint at 39 between autoclave 33 and shaft housing 21. An annular metal gasket ring 36, rectangular in cross section, is positioned on top of gasket 37. Annular retaining ring 18 threadedly engages the top of autoclave 33 at 34, the lower face of retaining ring 18 being disposed immediately above the upper face of gasket ring 36 when shaft housing 21 has been brought in closure contact with autoclave 33 by the action of retaining ring 18 bearing against an annular shoulder formed on shaft housing 21 at 91. A plu-

5 rality of bolts as at 38 pass through retaining ring 18 in threaded engagement therewith and bear against the upper face of gasket ring 36. A plurality of sockets as at 35 are provided around the periphery of retaining ring 18 for the reception of a bar tool to assist in threading retaining ring 18 into place.

10 Conduit 60 communicates from outside shaft housing 21 to the interior of autoclave 33. An indirect heat transfer coil 57 is provided with a plurality of spacers as at 56 which also serve as baffles with respect to fluid materials contained within the autoclave. Coil 57 is in flow communication with conduit 60 through a pressure connection at 59, providing means for supplying a cooling or heating medium to coil 57. An identical conduit in shaft housing and pressure connection (not shown) are employed for fluid exit from coil 57.

15 Agitator shaft 19 extends to a point near the bottom of autoclave 33 and is provided at its termination with an inverted cup 55 rigidly mounted thereon which partially encloses filter 54. A plurality of agitator blades as at 20 are also rigidly mounted on inverted cup 55 as shown.

20 Agitator shaft 19 extends through shaft housing 21, an elongated sleeve 63 being threaded into the bottom of shaft housing 21 and agitator shaft 19 extending through sleeve 63. A graphite or other suitable bearing 62 is provided between agitator shaft 19 and sleeve 63, cap 89 threaded on the end of sleeve 63 serving to retain graphite bearing 62 in the end of sleeve 63 as shown. Two sets of packing as at 65 and 73 separated by a lantern ring 66, are provided above the end of sleeve 63. Packing gland 74 bears against packing 73 and is secured by retainer 80 which threadedly engages the lower end of bearing housing 22. Lubricant is admitted to lantern ring 66 from reservoir 70 via conduit 69, valve 68 and conduit 67. Conduit 72 leads from the interior of autoclave 33 and is connected with lubricant reservoir 70 above the liquid level therein by means of conduit 71.

25 Conduit 64 passes through the side wall of shaft housing 21 and sleeve 63 to communication with the space between agitator shaft 19 and sleeve 63. Since the tolerance between agitator shaft 19 and graphite bearing 62 is not especially close, bearing 62 serving primarily to steady the lower end of agitator shaft 19, there is a tendency for certain types of materials at times placed in the autoclave, particularly slurries of finely divided pulverulent material, to work up between agitator shaft 19 and sleeve 63. In order to prevent damage to the shaft and the pressure packing under such conditions, an inert fluid or feed liquid or gas which is to be introduced into the autoclave may be passed under pressure through conduit 64 and down between agitator shaft 19 and sleeve 63, thereby flushing this area and avoiding the undesirable conditions noted above.

30 Ball bearings as at 75 are provided in bearing housing 22 at the upper end of agitator shaft 19 to resist the upward thrust forces of the shaft developed as a result of the pressure within the autoclave during operation.

35 The upper end of shaft housing 21 around packing 65 and 73 is provided with annular cooling jackets as at 76 and 78 through which a cooling fluid may be circulated.

40 The functions of the various elements of the autoclave assembly hereinbefore described are as follows:

The autoclave is charged with the materials which are to be processed either by disconnecting the head closure and lowering the autoclave from the head or, alternatively, when freely flowing liquids are to be charged, they may be passed through conduit 72 after temporarily removing the connection normally provided for conduit 74. If desired, another conduit such as at 72 may be provided in shaft housing 21 for filling purposes. When charging material which cannot be satisfactorily introduced through a conduit, bolts 38 are loosened and retaining ring 18 threaded out of engagement with autoclave 33. Carriage member 3, on which autoclave unit 8 is mounted by means of support bracket 97, is then lowered by means of worm gear unit 95 and roller chain 11, counterweight 13 rising in column member 2 as carriage member 3 is lowered. If carriage member 3 is lowered until it rests on column flange 32, autoclave unit 8 will tilt to the position shown in Figure II as the counterweight 13 is further raised by means of worm gear unit 95, due to the weight of the autoclave unit and the offcenter pivotal mounting of the autoclave unit on support bracket 97 at 9.

If desired for any reason, the autoclave jacket comprising outer shell 42, inner shell 43 and insulators 44, 45 and 46 may be lowered independently by loosening bolts 80, flange 79 and thermal insulators 48 being lowered with the autoclave jacket as a unit and autoclave 33 remaining attached to shaft housing 21.

The autoclave is closed by raising autoclave unit 8 by means of worm gear unit 95 until autoclave 33 is firmly seated against shaft housing 21 at 39, corrugated gasket 37 and gasket ring 36 are placed in position and retaining ring 18 is threaded into autoclave 33 seated on the shoulder of shaft housing 21 at 91. The final pressure seal is then made by tightening bolts 38. It will be seen that retaining ring 18 carries most of the pressure load against the bottom of shaft housing 21 when the autoclave is under pressure, gasket 37 being required only to prevent leakage around the joint between autoclave 33 and shaft housing 21 at 39. Bolts 38 are threadedly mounted in retaining ring 18, bearing against gasket ring 36 which in turn bears against gasket 37, and as a result are required to resist only the pressure load on the gasket. This construction permits the use of much lighter and more easily secured bolts than in the conventional autoclave closures wherein head bolts under tension load are required to resist the entire pressure load on the closure. Furthermore, since the bolts in the present instance are under compression rather than tension load, the failure of a bolt results in nothing more serious than slight leakage around the gasket, whereas in conventional tension bolt closures, failure of one or more of the bolts often results in a serious explosion or at least flying metal fragments which endanger the operator.

With the autoclave closed and charged, heat may be applied to the contents thereof either by means of external electrical heating elements as at 47 or by means of internal coil 57 through which a heated fluid may be passed. The two heating units may be employed simultaneously if desired and coil 57 also, of course, may be utilized for cooling purposes if desired by passing a cooled fluid or refrigerant therethrough. Efficient agitation of the contents of the autoclave is obtained through the action of agitator blades 20 in conjunction with baffles 56 mount-

ed on and carried by heating coil 57. This construction obviates the use of baffles of one sort or another on the interior walls of autoclave 33, the smooth walls of the present autoclave greatly facilitating cleaning operations and reducing initial construction costs. The pressure packing 65 and 73 on the agitator shaft 19 is gravity lubricated, lubricant reservoir 70 being positioned at a higher level than the packing and the pressure above the lubricant level in reservoir being equalized through conduits 71 and 72 which are in flow communication with the interior of autoclave 33. The flow of lubricant to the packing is controlled by means of valve 68 between conduits 67 and 69.

The autoclave may be discharged either by lowering autoclave body 33 from the head closure, as described above with regard to the filling operation, or through discharge outlet 80 in those instances where the contents are sufficiently fluid to pass through a conduit. If filtration of the contents of the autoclave is unnecessary, a plug or valve may be substituted for the filtering unit supported by bushing 51 as shown in Figure III.

In those instances where filtration is desired, the filtration unit shown in Figure III is preferably employed and the autoclave discharged by removing a valve normally provided in the threaded outlet end of bushing 51, the filtrate passing through disc filter 54, which may be adjusted by means of nut 88 as hereinbefore detailed, through the grooves in adjustment rod 53 and out through bushing 51 and the valve. The filtration may be carried out under the pressure existing in autoclave 33 after the processing of the contents has been completed, at atmospheric pressure by disconnecting conduit 71 and permitting pressure equalization within the autoclave or by controlled pressure through conduit 72. Inverted cup member 55 which partially encloses filter 54 materially assists in the rapid and complete drainage of the autoclave, since in the absence of this element the rate of discharge would decrease as the liquid level in the autoclave fell below the top of filter 54 with consequent release of the gas pressure through the top of filter 54. In the structure shown, a siphon-like effect is attained, i. e. the liquid level within inverted cup 55 remains above the top of filter 54 until the liquid level in the autoclave falls below the lower rim of inverted cup 55, thus utilizing the full filter surface until virtually all of the contents of the autoclave have been drained.

We claim as our invention:

1. In an autoclave assembly, the combination comprising a support upright, a pulley at the top of said upright, a carriage slidably mounted on said upright, a vessel pivotally mounted near the base thereof on said carriage, a counterbalance weight for said carriage and vessel, a flexible connector passing over said pulley joining said counterbalance weight and carriage whereby said carriage and vessel may be readily raised or lowered on said upright, and a closure for said vessel mounted on said upright near the upper limit of travel of said carriage on said upright.

2. In an autoclave assembly, the combination comprising a support upright, a pulley at the top of said upright, a carriage slidably mounted on said upright, a vessel pivotally and off center mounted near the bottom thereof on said carriage, a weight counterbalancing said carriage and vessel, flexible support means passing over said pulley and joining said weight and said carriage, whereby said carriage and said vessel

may be readily raised and lowered on said upright, and a closure for said vessel mounted near the top of said upright being positioned diametrically and vertically above said vessel on said carriage.

3. In an autoclave assembly, the combination comprising a support upright, a carriage member slidably mounted on said upright, a vessel pivotally and offcenter mounted near the base thereof on said carriage member, a sprocket wheel rotatably mounted above said support upright, flexible support means passing over and engaging said sprocket wheel and supporting said carriage member at one end and a counterweight disposed within said support upright at the other end, a closure for said vessel mounted on said upright near the upper limit of travel of said carriage member on said upright, a stop element mounted on said upright and limiting the lower limit of travel of said carriage member on said upright, and means for rotating said sprocket wheel and thereby raising and lowering said carriage member on said support upright.

4. In an autoclave assembly, the combination comprising a support upright, a carriage member slidably mounted on said upright, a pressure vessel pivotally and offcenter mounted near the base thereof on said carriage member, a first sprocket wheel rotatably mounted above said support upright, a second sprocket wheel rotatably mounted on said carriage member near the upper end thereof, a vertically adjustable counterweight disposed within said upright support, flexible support means attached to said counterweight at one end and to said carriage member at the other end, said flexible support means passing over and engaging said first sprocket wheel and passing under and engaging said second sprocket wheel, a closure for said vessel mounted on said upright near the upper limit of travel of said carriage member on said upright, a stop element mounted on said upright and limiting the lower limit of travel of said carriage member on said upright and means for rotating said first sprocket wheel and thereby raising and lowering said carriage member on said support upright.

5. In an autoclave, the combination comprising a pressure vessel including an opening therein, a closure element seating on an annular shoulder provided in said opening in said pressure vessel, an independent closure retaining ring threadedly engaging said pressure vessel, said retaining ring being freely mounted on said closure element and bearing against an annular shoulder provided on said closure element, a pressure sealing gasket covering the annular joint between said closure element and said pressure vessel, a gasket retaining ring supported on said pressure gasket and a plurality of bolts passing through said closure retaining ring in threaded engagement therewith and urging said gasket retaining ring against said pressure gasket, thereby forming a pressure seal between said closure element and said pressure vessel.

6. In an autoclave, the combination comprising a closed pressure vessel including a discharge outlet therein, filter means mounted in said discharge outlet and extending upwardly within the body of said pressure vessel, an agitator shaft rotatably mounted in said pressure vessel and extending downwardly into the body of said pressure vessel and an inverted cup element mounted on the end of said agitator shaft and extending below the upper end of said filter element.

7. In an autoclave, the combination comprising

ing a pressure vessel including an opening and a discharge outlet therein, closure means sealing said opening in said pressure vessel, filter means mounted in said discharge outlet and extending upwardly within the body of said pressure vessel, an agitator shaft rotatably mounted in said closure means and extending downwardly into said pressure vessel and an inverted cup element mounted on the end of said agitator shaft and extending below the upper end of said filter element.

8. In an autoclave, the combination comprising a pressure vessel including a top opening and a bottom discharge outlet therein, closure means sealing said top opening in said pressure vessel, an agitator shaft rotatably mounted in said closure means and extending downwardly into the body of said pressure vessel, an inverted cup rigidly mounted on the lower end of said agitator shaft, a disk filter mounted in said discharge outlet and extending upwardly into the body of said pressure vessel and into said inverted cup, said disk filter terminating above the lower rim of said inverted cup, an adjustment rod passing through said disk filter and means for adjusting the compression exerted on said filter disk by said adjustment rod.

9. In an autoclave, the combination comprising an open pressure vessel, closure means threadedly engaging said pressure vessel, a pressure sealing gasket disposed between said closure means and said pressure vessel, means threadedly engaging said closure means urging said gasket downwardly to form a pressure seal between said closure means and said pressure vessel, a pressure sealed agitator shaft rotatably mounted in said closure means and extending downwardly into the body of said pressure vessel, a discharge outlet in said pressure vessel, a filter element mounted in said discharge outlet and extending upwardly into the body of said pressure vessel and an inverted cup rigidly mounted on said agitator shaft above said filter element and extending below the top of said filter element.

10. In an autoclave, the combination comprising an open pressure vessel, closure means threadedly engaging said pressure vessel, a pressure sealing gasket disposed between said closure means and said pressure vessel, means threadedly engaging said closure means urging said gasket downwardly to form a pressure seal between said closure means and said pressure vessel, annular heating means depending from said closure means, baffle means mounted on said heating means, a pressure sealed agitator shaft rotatably mounted in said sealing means and extending downwardly into the body of said pressure vessel, an agitator rigidly mounted on said agitator shaft, said agitator being disposed adjacent said baffle means mounted on said heating element, an inverted cup mounted on the end of said agitator shaft, a discharge outlet in said pressure vessel, and a filter element mounted in said discharge outlet extending upwardly into the body of said pressure vessel and terminating within said inverted cup above the lower rim thereof.

11. In an autoclave, the combination comprising a pressure vessel including a top opening and a bottom discharge outlet therein, a closure element seating on an annular shoulder provided in said top opening in said pressure vessel, a closure retaining ring threadedly engaging said pressure vessel, said retaining ring being slidably and rotatably mounted on said closure element and bearing against an annular shoulder provided on

said closure element, a pressure sealing gasket covering the annular joint between said closure element and said pressure vessel, a gasket retaining ring supported on said pressure gasket, a plurality of bolts passing through said closure retaining ring in threaded engagement therewith and urging said gasket retaining ring against said pressure gasket, thereby forming a pressure seal between said closure element and said pressure vessel, an annular heat exchange coil depending from said closure element, the coils of said heat exchange coil being disposed adjacent the inner wall of said pressure vessel, means for circulating heat exchange media through said heat exchange coil, a pressure sealed agitator shaft rotatably mounted in said closure element and extending within the body of said pressure vessel, an agitator rigidly mounted on said agitator shaft in said pressure vessel, said heat exchange coil being disposed circumambient with respect to at least a part of said agitator, a plurality of vertical baffles mounted on said heat exchange coil adjacent said agitator, an inverted cup rigidly mounted on said agitator and terminating imme-

diate above said discharge outlet in said pressure vessel, a disk filter mounted in said discharge outlet and extending upwardly into the body of said pressure vessel and into said inverted cup, thermal insulating means disposed around said pressure vessel and supported by said pressure vessel and heating means disposed between said thermal insulating means and said pressure vessel.

10 12. In an autoclave, the combination comprising an open pressure vessel, a plug closure therefor, a pressure sealing gasket covering the joint between said pressure vessel and said plug closure, an independent retaining ring threadedly engaging the inside wall of said pressure vessel, said retaining ring being freely mounted on said plug closure and positioned above said gasket and studs threaded in said retaining ring for urging said pressure gasket downward to form a pressure seal between said pressure vessel and said plug closure.
